CORSET OR FOUNDATION GARMENT

Joseph J. Kispert, New Haven, Conn.

Application October 14, 1941, Serial No. 414,950

6 Claims. (Cl. 2—35)

This invention relates to an improvement in the construction of corsets, foundation garments, and the like.

At the present time, corsets and other garments of this character are manufactured in standard sizes and it is necessary for a merchant to stock all sizes in order that customers may be fitted. This requires a large stock and even then, difficulty is often experienced in fitting a customer who may have a waist of a certain size but hips which are out of proportion to the waist measurement. Therefore, a corset having the desired waist measurement will not fit properly about the hips, due to its hip measurement being too large or too small. Corsets and foundation garments as now made are not readily adjustable and sales are frequently lost, due to the fact that the merchant does not have in stock a corset of the standard size to fit the customer or the customer cannot be fitted with a corset of standard size and must purchase a custom made corset in order to secure a good fit.

Therefore, one object of the present invention is to provide a corset or foundation garment of such construction that temporary stitching at its sides may be ripped out and the garment then adjusted to provide a garment of the proper size and sewed with permanent stitching. It will thus be seen that a manufacturer may produce the garments in size groups, each garment covering a number of standard sizes, and the merchant can carry a small stock and fit customers of various sizes by selecting a garment from the proper size group and readily altering it to fit the customer.

Another object of the invention is to provide a garment of this character having overlapped sections temporarily sewed to each other, one section being provided with gauge markings for indicating the proper overlap of the companion section in order to convert the garment to the desired size.

Another object of the invention is to so arrange the gauge markings that they are in the form of lines of stitching which diverge toward the lower edge of the garment, size markings being provided at lower ends of the gauge lines to identify the same, and the gauge lines being readily distinguishable from each other in order that the overlapping portion of the garment may be positioned to dispose its edge in registry with a predetermined gauge line and then secured with a line of permanent stitching.

Another object of the invention is to provide a corset or foundation garment which is readily

adjustable for a predetermined size and, when adjusted and secured by permanent stitching, will be smooth and not bulky.

Another object of the invention is to provide a foundation garment of such construction that it may have a brassière forming a portion thereof adjusted for size as well as the body of the garment being adjustable for waist and hip measurements.

In the accompanying drawings:

Fig. 1 is a view looking at the outside of a corset of the improved construction.

Fig. 2 is a view looking at the inside of the corset.

Fig. 3 is a sectional view on an enlarged scale on the line 3—3 of Fig. 1.

Fig. 4 is a view similar to Fig. 3, showing the manner in which an adjustment is made for predetermined hip measurement.

Fig. 5 is a fragmentary view showing the manner in which the adjustable sections of the corset are initially overlapped and temporarily secured.

Fig. 6 is a fragmentary view looking at inner surfaces of lower portions of the overlapped portions of the corset.

Fig. 7 is a view looking at the outer side of a foundation garment having the improved construction.

Fig. 8 is a fragmentary view showing a modified construction.

Fig. 9 is a view showing the sections of Fig. 8 secured together in their initial position of adjustment.

Fig. 10 is a sectional view on the line 10—10 of Fig. 9.

Figs. 11 through 14 are diagrammatic views illustrating size groups obtainable with corsets constructed in accordance with this invention.

The corset illustrated in Figs. 1 through 6 of the drawings, may be formed of any suitable material and has a back section 1 and front sections 2 which have their inner or rear side edge portions secured to side edge portions of the back section and, together therewith, forming side portions for the corset. It is understood that the sections 1 and 2 are provided with the usual stays and that while the sections 2 have been shown provided with auxiliary flaps 2', these flaps may be dispensed with, if desired, or other flaps, girdles, or the like, incorporated with these sections.

At the present time, it is customary to manufacture corsets of a certain predetermined size, each corset retaining its original size or waist and hip measurement. Therefore, it is necessary for a merchant to purchase a large stock of cor-

sets of various sizes and, even then, it is often difficult to properly fit a customer, due to unusual hip and waist measurements of the customer. In the improved corset formed in accordance with this invention, the front sections 2 are provided along their inner side edge portions with groups of gauge markings 3, in the form of lines of stitching 4 which extend between upper and lower edges of the sections and converge upwardly with their upper ends intersecting at the waist line 5 of the corset, which may be its upper edge or spaced downwardly therefrom, according to the type and style of corset. These lines of stitching are readily distinguishable from each other and may be of contrasting colors so that they may be easily followed when side edge portions of the back section are disposed in overlapping relation to the front sections and sewed to the same by lines of temporary stitching 6, or permanent stitching 7. Each group of gauge lines covers a size range of several inches in the hip measurement and, initially, the overlapping portions of the front sections are so disposed that their inner side edges follow the central gauge line, indicated by the numeral 4' in Figs. 11 through 14, and designated "neutral zone" in these figures. The front sections, when so overlapped, are secured by the temporary stitches 6 which may be termed basting stitches, as they are of light thread and can easily be ripped out.

When a customer is being fitted, the attendant selects a corset of the proper waist measurement and, after applying it, ascertains whether the hip measurement is correct, or the customer may be measured for waist and hip measurements before the corset is applied. If it is found that the corset as originally assembled is the correct size at the waist and about the hips, it is merely necessary to secure the overlapped portions of the front sections by lines of permanent stitching. When, however, it is found that the hip measurement of the corset is too large or too small, the front sections are ripped loose from the back section and shifted to a position in which their inner side edges follow a gauge line 4 to provide a corset of the proper hip measurement. Permanent stitching 7 is then applied to firmly secure the front sections. This can be done in a few minutes and produces, in effect, a custom-made corset which fits properly and will be comfortable when worn and impart the desired compression and uplift. Size markings 8 are provided at lower ends of the gauge lines 4 in order that the proper gauge line for a corset having a predetermined hip measurement may be readily identified and followed when applying the detached front section and permanently sewing it to the rear section.

Referring to Figs. 11 through 14, it will be seen that a corset of the group sizes shown in Fig. 11, has a waist measurement of twenty-nine inches and a hip measurement between thirty-seven and forty-one inches. The corset of the size group shown in Fig. 12 has a thirty-one inch waist and is from thirty-nine to forty-three inches about the hips. The corset of Fig. 13 has a waist measurement of thirty-two inches and a hip measurement of between forty and forty-four inches, and that of Fig. 14 has a thirty-seven inch waist and between forty-five and forty-nine inches about the hips. These are merely examples of size groups and it is to be understood that in manufacture, other groups of predetermined waist and hip measurements may be provided.

In Fig. 7 there has been shown a foundation

garment of the improved construction. In this embodiment of the invention, the garment has a back section 9 formed with side panels or subsections 10 and 11, the side panels having stitches therein denoting gauge lines 12 corresponding to the gauge lines 4. The side sections are overlapped by inner or rear side edge portions of the front sections 13 and the side section 14 and the overlapping portions of these sections are initially temporarily stitched to the rear section centrally of the groups of gauge lines 12. When the garment is to be fitted to a customer, the waist and hip measurements of the customer are ascertained and the sections 13 and 14 are then ripped loose and shifted across the side panels of the rear section to dispose their rear side edges along the proper gauge lines where they are secured by permanent stitching. At lower ends of the gauge lines the inner surfaces of the side panels are provided with size markings for hip measurements and, at the intersecting upper ends of these gauge markings, the waist measurement of the garment is marked upon inner surfaces of the side panels. At its top, the foundation garment carries a brassière except that it has auxiliary sections 16 and 17, the rear ones 16 of these auxiliary sections being carried by the upper portion of the back section 9 of the garment and marked with gauge lines 18 and the front ones 17 of the auxiliary sections being disposed in overlapped relation thereto and initially secured by temporary stitching. By this arrangement, the brassière may be adjusted for size and the sections 17 permanently secured after being disposed in predetermined overlapped relation to the sections 16 with their inner side edges extending along the proper gauge lines 18.

Instead of merely overlapping the companion sections and disposing the inner side edge in position to extend along a selected gauge line sewed into the other section, the construction shown in Figs. 8, 9 and 10 may be employed. Referring to these figures, it will be seen that the rear section 19 has a group of gauge lines 20 stitched into it and it will be understood that size markings are provided at lower ends of these lines to indicate hip measurements and, at their intersecting upper ends, will be provided the waist measurements of the garment. The companion section 21 of the garment, instead of consisting of a single ply, has inner and outer plies 22 constituting walls of a pocket 23 into which the section 19 fits, as shown in Figs. 9 and 10. The section 19 is freely slidable into and out of the pocket when unsecured and when initially inserted, is secured by a line of temporary stitching 24 which holds the section 19 within the pocket with the outer side edge of the section 21 along the center gauge line. After the hip measurement of the customer has been ascertained, the temporary stitching is ripped out, the sections shifted to position disposing them in proper overlapped relation to each other, and the sections permanently sewed to each other. In either embodiment of the overlapped adjustment, the overlapping portions have smooth face to face engagement with each other and no bulges or the like will appear through a dress. It should be further noted that in case rubber in the garment should become unduly stretched before the garment is worn out, the adjustable sections may be ripped loose, proper adjustment made, and stitching applied to secure the sections in adjusted position.

The fact that the section 19 fits within a pocket

provides a stronger connection, as there are three layers of material sewed together and, since the plies 22 are united to each other, they are not liable to catch and be accidentally torn loose.

Having thus described the invention, what is claimed is:

1. In a garment of the character described, companion sections disposed one in overlapping relation to the other, one section being provided with a group of gauge lines converging and intersecting at the waistline of the garment, the other section being initially disposed substantially midway the width of the group of gauge lines and temporarily stitched to the first mentioned section whereby the said sections may be detached from each other and then shifted to a predetermined position of adjustment and permanently secured, said position being determined by one of said gauge lines.

2. In a garment of the character described, a body having companion vertically extending sections, one section being overlapped by the companion section and provided with a group of converging longitudinally extending gauge lines intersecting intermediate their ends at the waist line of the garment and at one end defining possible hip measurements within the scope of the group of lines, and means for temporarily securing the sections in overlapped face to face engagement with each other with the side edge of the overlapping section following one of the gauge lines.

3. In a garment of the character described, a body having companion vertically extending sections, one section being formed with a pocket having inner and outer walls and open along its outer side edge, the other section extending into the pocket and being provided with gauge markings converging at the waist line of the garment for indicating a permanent waist measurement of the garment, said markings indicating possible hip measurements within predetermined limits, and temporary stitching for initially securing the last mentioned section in the pocket and permitting ripping loose thereof for adjustment to an ascertained hip measurement.

4. In a garment of the character described, a body having companion vertically extending sections, one section having a side edge portion overlapped by the adjoining side edge portion of

the companion section and provided with a group of vertically extending gauge lines, a line at the center of said group being disposed perpendicular to the lower edge of the garment and constituting a neutral zone and lines at opposite sides of the center line constituting adjustment lines extending upwardly in converging relation to the center line and crossing said center line at approximately the waist line of the garment and then diverging upwardly at opposite sides of the center line, a size marking at the point at which said gauge lines intersect designating a permanent waist measurement, size markings at ends of said gauge lines designating anticipated 15 adjustments within the scope of the group of gauge lines, and temporary stitching securing the overlapping section upon the overlapped section in a neutral position disposing its side edge even with the said center line.

5. In a figure-controlling garment, means for facilitating the fitting thereof to an individual figure comprising adjacent garment sections in overlapping relation, one being provided with a group of converging gauge lines indicating the proper overlap for a group of different dimensions, and the other being temporarily secured by a line of basting stitches to the first, with its edge following the gauge line indicating normal figure proportions, whereby said sections may 20 readily be detached from each other, adjusted to the gauge line indicating the predetermined dimension which departs from normal figure proportions and then secured together in adjusted position by permanent stitching.

6. In a garment, companion sections having adjoining side edge portions disposed one in overlapping relation to the other, the said side edge portion of one section being provided with a vertically disposed group of gauge lines converging 25 toward and intersecting at one end of the group, a line midway the group being a neutral line, and the other section having its side edge initially disposed along said neutral line and temporarily 30 stitched to the first mentioned section whereby the sections may be ripped apart and then shifted transversely to a predetermined position of adjustment determined by another one of the gauge lines and permanently secured along the 35 last mentioned gauge line.
